BOTTLE

Alain Pieyre de Mandiargues, Paris, France, assignor to Parfums Guy Laroche, Paris, France

Filed Nov. 13, 1970, Ser. No. 25,965

Claims priority, application France May 13, 1970

Term of patent 14 years

Int. Cl. D9—01

U.S. Cl. D9—169

FIG. 1

FIG. 2

FIG. 3

FIG. 4

FIG. 5

FIG. 6

FIG. 1 is an elevational view of a bottle showing my new design;

FIG. 2 is an elevational view looking from the left of FIG. 1, the opposite side being the same in appearance as the side shown;

FIG. 3 is a cross-sectional view taken through the center of the circular depressions on the sides;

FIG. 4 is a top plan view;

FIG. 5 is a bottom plan view; and

FIG. 6 is a perspective view thereof.

I claim:

The ornamental design for a bottle, as shown and described.
